UNITED STATES PATENT OFFICE.

WILSON E. PORTER, OF NEW HAVEN, CONNECTICUT, ASSIGNOR TO THE NEW HAVEN CLOCK CO., OF NEW HAVEN, CONNECTICUT, A CORPORATION.

STEM-WINDING AND STEM-SETTING WATCH.

1,054,447.

Specification of Letters Patent.

Patented Feb. 25, 1913.

Application filed November 7, 1911. Serial No. 658,930.

To all whom it may concern:

Be it known that I, WILSON E. PORTER, a citizen of the United States, residing at New Haven, in the county of New Haven 5 and State of Connecticut, have invented a new and useful Improvement in Stem-Winding and Stem-Setting Watches; and I do hereby declare the following, when taken in connection with the accompanying drawings and the letters of reference marked thereon, to be a full, clear, and exact description of the same, and which said drawings constitute part of this specification, and represent, in—

15 Figure 1 a view in front elevation of a stem-winding and stem-setting watch constructed in accordance with my invention. Fig. 2 a view of the watch with the dial and dial-plate removed, showing the winding-wheel and dial-wheel in elevation, and the pendant in longitudinal section, with the stem pushed inward into its normal position for winding. Fig. 3 a corresponding view with the parts adjusted for setting by the 20 pulling out of the stem. Fig. 4 a broken view in vertical section on the line *a—b* of Fig. 2. Fig. 5 a detached perspective view of the yoke. Fig. 6 a detached sectional view of the shouldered stud.

25 Heretofore the cheaper grades of stem-winding and stem-setting watches have been set by pushing in the stem, which is objectionable on account of the danger to which such watches are constantly exposed of having the hands shifted in position by the accidental pushing in of the stem by pressure upon the crown of the watch when in the wearer's pocket as he bends forward, or by the pressure of the swivel of the chain 30 upon the crown, or in some other accidental way. These objections have been avoided in high grade stem-winding and stem-setting watches by constructing them to set by pulling out the stem, but that principle of operation has heretofore been too expensive for application to stem-winding and stem-setting watches of the cheaper class.

35 My present invention aims to confer upon the cheaper grades of stem-winding and stem-setting watches the advantages proceeding from pulling out the stem to set.

40 With these ends in view, my invention consists in a stem-winding and stem-setting watch having certain details of construction 45 and combinations of parts as will be here-

inafter described and pointed out in the claims.

In carrying out my invention, I employ a yoke 2 swiveling upon a shouldered stud having a large bearing-head 3, a shoulder 4 and a rivet 5, which latter is headed down upon the inner face of the front movement-plate 6, upon the outer face of which the said yoke is located. The said yoke 2 swivels or rocks upon the shoulder 4 which also 60 forms a bearing for the winding-and-setting wheel 7 which bears directly upon the outer face of the said front movement-plate 6 and meshes into the winding-and-setting pinion 8 which is located in a plane at a 70 right angle to the plane of the watch and rests upon a bridge 9 interposed between the said front movement-plate 6 and the rear movement-plate 10, the said pinion 8 being permanently secured to the bridge 9 with 75 freedom to revolve, by its hub 11 which passes downward through the bridge and is headed over upon a washer 12 bearing against the inner face thereof. The said yoke 2 carries at its lower end an intermediate winding-and-setting wheel 13 constantly 80 in mesh with the wheel 7 aforesaid, and interposed between the main winding-wheel 14 of the watch and the dial-wheel 15 thereof, the said wheel 13 being normally held in 85 engagement with the main winding-wheel 14 by a plate spring 16 secured to the outer face of the front movement-plate 6 and engaging with an arm 16^a offsetting from the right hand edge of the yoke 2. 90

At its upper end the yoke is formed with an outwardly extending operating-arm 17 turned inward at its outer end through a clearance-notch 18 in the plate 6 into position to engage directly with the beveled or rounded upper face of an operating-cone 19 mounted near the inner end of a longitudinally movable and rotatable winding-and-setting stem 20 having its inner end squared and passed through a squared opening in the pinion 8, whereby the stem is free to be moved longitudinally with respect to the pinion which, however, remains coupled therewith for rotation thereby. The said stem passes outward through a hollow pendant 21 secured at its inner end to the casing 22 and provided at its outer end with a head 23 carrying a bow 24. The stem 20 is furnished at its projecting outer end with a crown 25 of ordinary construction. Within 100 105 110

the pendant 21, I locate a spring 26 encircling the outer end of the stem and interposed between the closer outer end of the pendant and a collar 27 on the stem, this spring exerting a constant effort to push the stem inward and maintain it in its winding position. The spring 26 therefore supplements the action of the spring 16 already mentioned. When the crown is seized by 10 the finger and the stem 20 pulled outward against the tension of the springs 16 and 26, the rounded upper surface of the operating-cone 19 carried by the stem 20, engages with the inner edge of the arm 17 of the yoke 15 which is thus rocked from left to right on the shoulder 4, whereby the intermediate winding-and-setting wheel 13 is demeshed from the main winding-wheel 14 and swung from right to left into engagement with the 20 dial-wheel 15, whereby the watch is adjusted for setting and maintained in this adjustment as long as the outward draft is maintained upon the stem. However, as soon as the outward pull of the fingers upon the stem is 25 removed, the springs 16 and 26 automatically operate to restore the stem to its normal or inward position, whereby the yoke is allowed to swing from left to right, and thus demesh the wheel 13 from the dial-wheel 15, 30 and remesh it with the main winding-wheel 14.

It will thus be seen that by extremely simple means and without the addition of supplemental wheels or levers, I provide for 35 setting the watch by the pulling out of the stem rather than on pushing in the stem, whereby the watch is made more reliable as a time-piece since the accidental shifting of the hands is avoided for it is not conceivable that in any use of the watch, the stem 40 may be accidentally pulled outward. By locating the yoke upon the outer face of the front movement-plate and forming it with an outwardly extending operating-arm turned 45 inward at its outer end for engagement directly with the stem, I secure a great economy of space and avoid the duplication of parts and wheels which would otherwise be necessary.

50 I claim:—

1. In a stem-winding and stem setting watch, the combination with a longitudinally movable and rotatable winding-and-setting stem, of a yoke located upon the outer side of the front movement-plate of the watch and engaging directly with the said stem for being positively operated thereby when the stem is pulled outward, a winding-and-setting wheel mounted upon the yoke, a 55 winding-wheel with which the said winding-

and-setting wheel carried by the yoke is normally engaged, a dial-wheel with which the said wheel carried by the yoke is engaged when the yoke is swung by the pulling out of the said stem, and means for normally holding the yoke with its wheel meshed into the main winding-wheel. 65

2. In a stem-winding-and-stem-setting watch in which the setting of the watch is effected by the pulling out of the winding stem, the combination with a longitudinally movable and rotatable stem, of an operating-cone carried thereby, a yoke located upon the outside of the front movement-plate of the watch and provided with an outwardly 70 extending arm turned inward at its outer end to engage directly with the upper face of the said cone, whereby the yoke is positively operated by the cone when the stem is pulled outward, an intermediate winding-and-setting wheel mounted upon the yoke, a winding-wheel and a dial-wheel, and a spring co-acting with the yoke for normally 75 maintaining the engagement of the wheel carried by it with the main winding-wheel 80 of the watch.

3. In a stem-winding-and-stem setting-watch in which the stem is pulled out for setting, the combination with a longitudinally movable and rotatable stem, of a winding-and-setting pinion through which the stem passes and which is revolved by it, a winding-and-setting wheel constantly meshing with the said winding-and-setting pinion, a yoke located upon the outer face of 95 the front movement-plate of the watch and formed with an outwardly extending arm co-acting directly with the said stem for positively swinging the yoke when the stem is pulled outward, a shouldered stud upon 100 which the yoke swivels and upon which the said winding-and-setting wheel turns, an intermediate winding-and-setting wheel meshing into the said winding-and-setting wheel and mounted upon the yoke at the lower 105 end thereof, a main winding-wheel, a dial-wheel, and a spring normally maintaining the intermediate winding-and-setting wheel in mesh with the main winding wheel, whereby the stem must be pulled outward 110 preparatory to swinging the yoke to engage the intermediate winding-and-setting wheel with the dial wheel for setting the watch.

In testimony whereof, I have signed this specification in the presence of two subscribers 115 and witnesses.
